UNITED STATES PATENT OFFICE.

FRIEDRICH WEIHENMEYER, OF ZUFFENHAUSEN, GERMANY.

DEVICE FOR IMPROVING THE FULLNESS OF SOUND AT THE STRIKING OF TIMEPIECES
AND CLOCKS HANGING ON THE WALL.

Application filed January 26, 1924. Serial No. 688,833.

To all whom it may concern:

Be it known that I, FRIEDRICH WEIHENMEYER, a citizen of the German Republic, residing at Zuffenhausen, Germany, have invented certain new and useful Improvements in a Device for Improving the Fullness of Sound at the Striking of Timepieces and Clocks Hanging on the Wall, of which the following is a specification.

10 The striking of time-pieces and clocks hanging on the wall leaves much to be desired as regards fullness, strength and sonorousness of sound. The invention has for its object to eliminate this inconvenience by constructing the back wall of the clock-case, in order to avoid the gong-like sound which buzzes in clock-cases and is different every time the clock is striking, in such a manner that a hollow space is 20 formed by means of a hollow frame which is in contact with fluted wooden supports on which a slightly stretched sounding board provided with ribs is mounted. By the slight stretching or tensioning of the sounding board a strong transmission of the gong-like sound upon comparatively narrow ledges is ensured, this sound being further transmitted by the hollow spaces or flutes to another hollow frame so that a 30 perfect acoustic in the space is ensured.

The invention will be best understood from a consideration of the following detailed description taken in connection with the accompanying drawings forming a part 35 of this specification, with the understanding that while on the drawings one embodiment of the invention is disclosed, the invention is not confined to any strict conformity with the showing of the drawings, 40 but may be embodied in any manner which does not make a material departure from the salient features of the invention.

In the drawings:

Fig. 1 shows the back wall for a time-piece case.
Fig. 2 is a cross section on line A—B of Fig. 1.

Fig. 3 is a vertical section on line C—D of Fig. 1.

Fig. 4 is a perspective view partly in section.

According to the invention a hollow frame *e* is mounted through the intermediary of wooden supports *b* stayed by means of inclined ribs *c*, said hollow frame forming the rear wall of the time-piece-casing. By the staying by means of the ribs *c* a slightly vaulted shape is given to the sounding board *a*. The outer end of the sounding board is in contact with the comparatively narrow surfaces of the wooden supports *b*, this surface having longitudinal flutes *d* extending from one end to the other. The hollow surfaces formed by the flutes *d* in the wooden supports *b* are covered to the rear by a hollow frame composed of wooden ledges *e* enclosing hollow spaces *e'*, said frame being open at the centre so that the intensified gong-like sound can escape through this open central part of frame *e*. In this manner the gong-like sound is greatly strengthened and held together, wherefrom results a fullness of sound which hitherto could not be attained in clock cases.

I claim:

Device for improving the fullness of sound at the striking of time-pieces and clocks hanging on the wall comprising in combination with the clock-case a sounding board, inclined ribs for staying the sounding board, a hollow frame open at the centre forming the back wall of the clock case and wooden supports fluted in longitudinal direction inserted between said sounding board and said hollow frame.

In testimony whereof I affix my signature in presence of two witnesses.

FRIEDRICH WEIHENMEYER.

Witnesses:

VIKTOR ZENT,
ERIC W. SPITZ
